(57) **CLAIM**

The ornamental design for an antenna, as shown and described.

DESCRIPTION

FIG. 1 is an isometric view of an antenna;

FIG. 2 is a top plan view thereof;

FIG. 3 is an isometric view of an antenna shown in FIG. 1 in an alternate configuration; and,

FIG. 4 is an alternate isometric view thereof.

The broken lines illustrate environmental subject matter and form no part of the claimed design.
